UNITED STATES PATENT OFFICE.

JOHN WHITEHEAD, OF FIUME, AUSTRIA-HUNGARY.

TORPEDO-LAUNCHING APPARATUS.

SPECIFICATION forming part of Letters Patent No. 608,814, dated August 9, 1898.

Application filed November 26, 1897. Serial No. 659,913. (No model.)

To all whom it may concern:

Be it known that I, JOHN WHITEHEAD, manufacturer, a citizen of Great Britain, residing at Fiume, Empire of Austria-Hungary, have invented certain new and useful Improvements in Torpedo-Launching Apparatus; and I do hereby declare the following to be a full, clear, and exact description of the invention, such as will enable others skilled in the art to which it appertains to make and use the same.

This invention relates to improvements in apparatus for launching torpedoes, and more particularly to apparatus for launching torpedoes under water from the broadside of a vessel in motion or from any fixed point in a stream.

The object of the said invention is to provide a means for launching torpedoes under water in such a manner that the torpedo will not be damaged or deflected by the water-pressure when emerging from the ship's side.

The said invention consists in inclosing the torpedo-ejecting tube in a water-tight casing extending from the side of the ship inward, the outer end of the casing registering with an opening in the ship's side and there provided with a sluice-valve by which that end of the casing may be closed or opened to the water.

The invention consists, further, in providing the ejecting-tube with a shield attached thereto and extending forward thereof, the said shield being substantially U-shaped in cross-section, the bottom of the U constituting the rear side or back of the shield and composed of two swinging doors, while the opposite side is left open.

The ejecting-tube and the shield are mounted upon suitable running-gear within said casing. When launching a torpedo, the sluice at the ship's side, normally closing the outer end of the casing, is opened. The impulse-tube, together with the shield, is pushed outward in the casing until the shield projects from the ship's side a distance approximately equal to the length of the torpedo. The torpedo is then launched by expelling it from the impulse-tube, and as it moves along the shield it is supported by the closed back thereof, and thus protected against strain from water-pressure acting on part of its length

only. When the torpedo is entirely outside of the ship's side, but still within the shield, the swinging doors constituting the back wall of the shield and against which the torpedo rests are automatically opened, thus releasing the torpedo at an instant when the water-pressure is upon the whole length thereof. The torpedo may then continue its course without having been deflected therefrom by the pressure of the water upon a part of its length only at one time and without having been subjected to the injurious strains consequent upon such action of the water. The torpedo having been ejected, the shield is drawn back into the casing, the sluice is closed, as also the doors of the shield, the water is removed from the casing, and the apparatus is ready for charging again.

In order that my invention may be more clearly understood, the same will be described in greater detail, reference being had to the accompanying drawings, in which—

Figure 1 is a fragmentary plan view of the launching apparatus constituting my invention with the top plate of the casing removed, some of the parts being shown in section. Fig. 2 is a vertical transverse section taken along the line 2 2, Fig. 1, and looking in the direction of the arrow. Fig. 3 is a vertical transverse section taken along the line 3 3, Fig. 1, and looking in the direction of the arrow. Fig. 3^a is a detail side elevation of the cylinder and arrangement for actuating the locking-rod. Fig. 4 is a front elevation, partly in section, of the charging apparatus; and Fig. 5 is a side elevation of the same. Fig. 6 is a plan view showing the arrangement of the apparatus on board ship, the port apparatus being ready to launch the torpedo, while the starboard apparatus is shown with the shield drawn back into the casing. Fig. 7 is a vertical section of a ship, showing the apparatus as arranged in Fig. 6; and Fig. 8 is a horizontal section taken along the inclosing case and showing the impulse-tube and shield in plan.

Similar letters refer to similar parts throughout the several views.

The apparatus embodying my invention consists, among other parts, of an impulse-tube *a* for ejecting the torpedo *A*. To this ejecting-tube is attached a shield or scoop *b*.

This shield is substantially U-shaped in cross-section, is exactly in line with the impulse-tube, and when extended beyond the ship's side has its open side presented broadside to the water in motion. The side of the shield opposite from the open side consists of two swinging doors *c c*, extending approximately the whole length of the shield. The doors are hinged, as at *c⁰*, to the top and bottom of the shield.

The doors *c c* are adapted to be locked together in the closed position by the rod *d*, extending longitudinally of the shield and carried in and guided by the eyes *c'*, secured at intervals to one of the doors. The other door is provided with a plurality of eyes *c²*, so located that when the doors are closed the eyes *c'* will register with the eyes *c²*, one of the latter being preferably between two of the former. The eyes on one door are slotted longitudinally, as shown most clearly at *c³*, Fig. 2, the slot being located at that point of the eye where the rod would engage it in closing the doors. The rod *d* is turned down to a reduced diameter at points *d'* along its length, the distance between such reduced portions corresponding to the distance between eyes *c²*. This reduced portion of the rod is made slightly less in diameter than the width of the slots in the eyes *c²*; but the slots are narrower than the full portion of the rod, so that when the full portion of the rod *d* is within the eyes the doors will be locked, but when the rod is shifted laterally and the reduced portions *d'* of the rod are brought within the eyes *c²* and opposite the slots *c³* the rod may readily escape from the eyes *c²* and the doors will thus be unlocked. The doors are thus locked in the closed position by the rod and eyes and unlocked by the shifting rod, the rod being adapted to move freely to and fro. This longitudinal movement of the bar *d* is effected by the action of a piston *e*, working in a pressure-cylinder *f*.

A lever *h* is secured at one end to the rod of the piston *e* and is provided at its other end with a lug *h²*, which latter engages the end of the rod *d* nearest the impulse-tube.

When the torpedo has reached that point in its forward motion in being launched when its tail comes opposite the pressure-cylinder, the tail of the torpedo strikes a lever *h*, which is caused thereby to operate upon a lug *g*, which actuates an escape-valve and releases the air-pressure upon the back of the piston. Air under pressure supplied to the said cylinder from any convenient source then acts on the front of the piston and shifts the rod *d* to that position, when the doors *c c* will be unlocked.

The impulse-tube *a* and shield *b* are adapted to travel longitudinally in a water-tight casing *l* on ways or guides *m*, secured to the said casing, and in which run the rollers *n*, carried by the carriages *n'*, secured to the shield. The motion is imparted to the shield and tube by the screw *i*, journaled in the cas-

ing *l* and engaged with a nut *i'*, carried by the impulse-tube. The screw *i* may be operated by any suitable motor *k*. The casing *l* opens at one end into an opening in the ship's side and is there provided with a sluice-valve *o* and is made of sufficient length to entirely inclose the impulse-tube and shield when the same are drawn into the casing. The casing is provided with a lateral opening at one side for the introduction of the torpedo into the impulse-tube and is there provided with a door *p*. This door *p* consists of a metal plate with ribs *p²*, which are adapted to be engaged by the clamping-screws *p³*, carried by the hinged arms *p'*. The arms *p'* carry at their upper ends hinged locking-arms *p⁴*, which engage lugs *p⁵* on the casing *l*.

The torpedo may be entered into the impulse-tube at the breech end, and when such a method is resorted to altogether the side door *p* of the casing may be dispensed with; but to save room, which is particularly important when the apparatus is used on board a ship, it will be found preferable to provide the casing with such an opening as door *p*, through which the torpedo may be introduced laterally into the shield when the shield-doors are open and thence pushed backward into the impulse-tube.

I have devised a convenient carriage for transporting the torpedoes and introducing them into the casing, as shown in Figs. 4 and 5, where *q* and *r* represent arms which support the torpedo by its after end and by a removable gudgeon *v*, screwed into its nose. Horizontal bars *s* carry the arms *q* and *r* and are provided with racks *s'*, which engage pinions *u*, carried in a frame *t*.

The frame *t* is mounted upon suitable running-gear *t'*, which travels upon guides or rails *t²* and *t³*. Horizontal motion to and from the casing may be given the torpedo supported by the arms *q* and *r* by operating the pinions *u* and wheels *u'*, and horizontal movement along the length of the casing may be given the torpedo by moving the whole carriage or frame *t* upon the rails *t²* and *t³* by operating the hand-wheel *w*, which is secured to the upper end of a shaft *w'*, which is parallel to the frame *t* and carries at its lower end a pinion *w²*, which engages a rack *w³*, formed on the rail *t³*.

The door of the casing *l* being open, the torpedo is placed upon the arms *q* and *r*, as above explained, and carried forward toward the casing *l* by actuating the hand-wheels *w'* or other suitable mechanism. In this way the torpedo is carried bodily into the shield. The arm supporting the tail of the torpedo is then partially rotated, so as to free it from the torpedo, and is then drawn back to its original position. The frame *t*, together with the torpedo, is then moved longitudinally toward the breech of the impulse-tube, pushing the torpedo before it, which then slides along the bottom of the shield *b* and thence into

the impulse-tube until the tail of the torpedo touches the breech-cover of the impulse-tube.

The torpedo being in the impulse-tube, the further operations of launching it are as follows: The door of the outer casing *l* being open, the swing-doors *c c* of the shield are closed by hand or otherwise, the reduced portions of the locking-bar *d* coming opposite and passing through the slots *c²* of the eyes *c²*. The end of the bar *d* is then coupled with the lever *h* and the locking-bar is moved inward either by hand or by actuating the valve-gear of the cylinder *f*, whereby the full portions of the locking-bar are caused to enter into the eyes *c²*, thus locking the doors in their closed position. The door of the outer casing *l* is then closed and locked, the sluice-valve *o* is opened, and the impulse-tube, together with the shield, is run out by means of the motor which actuates the screw *i* until approximately the whole of the shield has entered into the water. The torpedo is then ejected by admitting air under pressure into the impulse-tube or by any other suitable means and continues its course along the shield until a lug near the extreme after end of the torpedo strikes the toe of the lever *h*, raising the escape-valve *g* or otherwise opening it and permitting the new unbalanced air-pressure on the front side of the piston to draw this piston back, thus unlocking the swinging doors *c c*, which are then opened by the pressure of the water. The torpedo is thus set free at a moment when the pressure of the water due to the speed of the ship or to the current of the stream acts simultaneously on its whole broadsides. In this way the torpedo is not subjected to any bending strains at the moment of leaving the tube and may be launched without damage or undue deflection at any speed. The impulse-tube, together with the shield, is then drawn back into the casing, the sluice is closed, and the water pumped out of the casing.

Obviously I may make many changes in the above-described apparatus without departing from the spirit of my invention; but

What I claim, and desire to secure by Letters Patent of the United States, is—

50 1. In a torpedo - launching apparatus, the combination with an impulse-tube, of a forwardly-extending shield secured thereto, the said shield being open on one side and provided with swinging doors on the side opposite from the said open side, substantially as described.

2. In a torpedo - launching apparatus, the combination with a casing communicating with the water, of an impulse-tube carried within the said casing; a shield having one side constantly open, the said shield forming an extension of and being rigidly connected with said impulse-tube; doors arranged at the back of said shield; means for locking said doors in closed position, and means for unlocking the same, substantially as described.

65 3. In a torpedo - launching apparatus, the

combination with a casing communicating with the water, of an impulse-tube carried within said casing; a shield having one side 70 constantly open, the said shield forming an extension of and being connected with said impulse-tube; doors arranged at the back of said shield; means for locking said doors and means for automatically unlocking said doors 75 when the torpedo has passed fully into the shield and without the said casing, substantially as described.

4. In a torpedo - launching apparatus, the combination with a casing adapted to communicate with the water, of an impulse-tube carried within said casing; a shield having one side constantly open, the said shield forming an extension of and secured to said impulse-tube; hinged doors composing the back 85 of said shield; eyes secured at intervals near the edge of one of the said doors; a bar carried by such door and adapted to slide to and fro in said eyes, parts of said bar being reduced in diameter; slotted eyes secured to the other door and adapted to come in line with the first-mentioned eyes and opposite the reduced portions of the said bar and means for moving said bar to and fro longitudinally, substantially as described. 95

5. In a torpedo-launching apparatus, the combination with a casing adapted to communicate with the water, of an impulse-tube carried within said casing; a shield having one side constantly open, the said shield forming 100 an extension of and secured to said impulse-tube; hinged doors extending along the length of said shield and forming the back thereof; eyes secured at intervals near the edge of one of the said doors; a bar carried 105 by such door and adapted to slide to and fro in said eyes, parts of said bar being reduced in diameter; slotted eyes secured to the other door and adapted to come in line with the first-mentioned eyes and opposite the reduced 110 portions of the said bar, the slots in said slotted eyes being smaller than the full portions of said rod and large enough to let the reduced portions of said rod pass through them, and means for moving said bar to and 115 fro longitudinally, substantially as described.

6. In a torpedo-launching apparatus, the combination with a casing adapted to communicate with the water, of an impulse-tube carried within said casing; a shield having one 120 side constantly open, the said shield forming an extension of and secured to said impulse-tube; hinged doors extending along the length of said shield and forming the back thereof; eyes secured at intervals near the 125 edge of one of the said doors; a bar carried by such door and adapted to slide to and fro in said eyes, parts of said bar being reduced in diameter; slotted eyes secured to the other door and adapted to come in line with the 130 first-mentioned eyes and opposite the reduced portions of the said bar, the slots in the said slotted eyes being smaller than the full portions of said rod and large enough to let the

reduced portions of said rod pass through them; means for moving said bar to and fro longitudinally and means for moving the shield together with the impulse-tube within 5 said casing until the shield extends approximately its whole length into the water, substantially as described.

7. In a torpedo-launching apparatus, the combination with a casing adapted to communicate with the water, of an impulse-tube carried within said casing; a shield having one side constantly open, said shield being connected with said impulse-tube and extending forward in line therewith; hinged doors forming 10 the back of said shield; means for locking said shield; a cylinder and a piston working therein; means whereby the said piston is caused to unlock the said doors when the 15 torpedo has passed wholly into the shield on being launched, substantially as described.

8. In a torpedo-launching apparatus, the combination with a casing adapted to communicate with the water, of an impulse-tube carried within said casing; a shield having one 25 side constantly open, said shield being connected with said impulse-tube and extending forward in line therewith; hinged doors forming the back of said shield; a locking-rod extending longitudinally of said shield and 30 adapted to lock said doors in the closed position; a cylinder and a piston working therein; a lever adapted to connect the said locking-rod with the said piston, and means for causing the piston to shift the said locking-rod 35 and thereby unlock the said shield-doors as the torpedo passes wholly into the said shield, substantially as described.

9. In a torpedo-launching apparatus, the combination with a casing adapted to communicate with the water, of an impulse-tube carried within said casing; a shield having one 40 side constantly open, said shield being connected with said impulse-tube and extending forward in line therewith; hinged doors forming 45 the back of said shield; a locking-rod extending longitudinally of said shield and adapted to lock said doors in the closed position; a cylinder and a piston working therein; a lever adapted to connect the said locking- 50 rod with said piston; a second lever for controlling the pressure on said piston, said lever adapted to be engaged by the rear end of the torpedo as it passes the lever and thus to put said piston in motion and unlock the said 55 doors, substantially as described.

10. In an apparatus for launching torpedoes, the combination with a casing adapted to communicate at one end with the water, of a sluice-valve adapted to close that end of the 60 said casing; an impulse-tube carried within said casing; a shield secured to and forming a forward extension of said tube; hinged doors forming the back of said shield; means for locking and unlocking said doors; running- 65 gear mounted in said casing and secured to said shield; means for imparting travel to said running-gear and longitudinal motion to

said tube and shield, substantially as described.

11. In an apparatus for launching torpedoes, the combination with a casing adapted to communicate at one end with the water, of a sluice-valve adapted to close that end of the 70 said casing; an impulse-tube carried within said casing; a shield secured to and forming a forward extension of said tube; hinged doors forming the back of said shield; means for locking and unlocking said doors, running-gear mounted in said casing and secured to 75 said shield; a horizontal screw journaled in said casing; a nut mounted on said screw and secured to said shield and means for rotating said screw, thus imparting motion to the said tube and shield, substantially as described. 85

12. In an apparatus for launching torpedoes, the combination with a casing adapted to communicate at one end with the water, of a sluice-valve adapted to close that end of the 90 said casing; a water-tight door at one side 95 of said casing for the admission of the torpedo; an impulse-tube carried within said casing; a shield secured to and forming a forward extension of said tube; hinged doors forming the back of said shield; means for locking said doors in the closed position; means for shifting the shield together with the impulse-tube within said casing until the 100 shield has entirely entered the water and means for automatically unlocking said doors when the torpedo has wholly entered the shield, substantially as described.

13. In a torpedo-launching apparatus, the combination of a casing leading into the water, of a sluice-valve adapted to close the outer 105 end of such casing and of an impulse-tube within such casing with a shield substantially U-shaped in cross-section adapted to have its open side exposed to the pressure of the moving water and forming an extension of and 110 being rigidly connected with the impulse-tube; doors arranged at the opposite side of the said shield and extending along its whole length and pivoted on axes on the top and bottom of such shield parallel to the longitudinal axis of the latter; means for closing such doors; means for locking such doors in their closed position and for unlocking the same; means for moving the shield together with the impulse-tube within the casing until 115 the shield has entirely entered into the water, substantially as described.

14. In a torpedo-launching apparatus, the combination with a casing leading into the water, a sluice-valve adapted to close the outer 125 end of such casing and an impulse-tube within such casing, of a shield substantially U-shaped in cross-section adapted to have its open side exposed to the pressure of the moving water and forming an extension of and 130 being rigidly connected with the impulse-tube; doors arranged at the opposite side of the said shield from the open side and extending along its whole length and pivoted on axes

- on the top and bottom of such shield parallel to the longitudinal axis of the latter; means for closing such doors; eyes secured at intervals to the edge of one of the doors; a bar carried by such door and adapted to slide to and fro in the said eyes, parts of the said bar being reduced in diameter; slotted eyes secured to the edge of the other door and adapted to come in line with the first-mentioned eyes 5 and opposite the reduced portions of the said bar, the slots in the slotted eyes being smaller than the full portions of the bar but large enough to let pass through the reduced portions of such bar; a cylinder; a piston in the said cylinder; a lever adapted to connect the 45 piston with the said bar; means for admitting pressure on one side of the piston and relieving the same; a lever secured with such means, said lever being actuated by the moving torpedo; means for moving the shield together with the impulse-tube within the casing until the shield has entirely entered into water, substantially as described. 50
- 10 15. In a torpedo-launching apparatus, the combination with a casing leading into water, a sluice-valve adapted to close the outer end of such casing and an impulse-tube within such casing, of a shield substantially U-shaped in cross-section adapted to have its open side exposed to the pressure of moving 60 water and forming an extension of and being rigidly connected with the impulse-tube; doors arranged at the opposite side of the said shield and extending along its whole length and pivoted on axes on the top and bottom of 65 such shield parallel to the longitudinal axis of the latter; means for closing such doors; means for locking such doors in their closed position and for unlocking the same; means for moving the shield together with the impulse-tube within the casing until the shield has entirely entered the water, substantially 70 as described. 75
- 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580

In testimony whereof I affix my signature in presence of two witnesses.

JOHN WHITEHEAD.
